THEURE WILHELM ALM, OF STEWART MANOR, NEW YORK, ASSIGNOR TO INTERNATIONAL CIGAR MACHINERY COMPANY, A CORPORATION OF NEW JERSEY

FLEXIBLE KNURLER FOR CIGAR MACHINES

Application filed May 4, 1929. Serial No. 260,555.

This invention relates to an improvement in a cigar knurling device.

The knurlers heretofore in commercial use have always been cup-shaped devices, formed in one piece, adapted to fit only cigar heads and shoulders which are exactly alike, and unyielding to irregularities of the cigar. But cigars do vary slightly at the head and shoulders, and knurlers of the old type do not properly smooth the wrapper down on cigars in instances where there is some irregularity in the shape of the head or shoulder. The main object of the present invention is the production of a knurling device for rotatably engaging and yieldingly following irregularities of the head and shoulder of a cigar to smooth its wrapper thereon. With this and other objects not specifically mentioned in view, the invention consists in certain constructions and combinations which will be hereinafter fully described and then specifically set forth in the claims hereunto appended.

In the accompanying drawings which form a part of this specification and in which like characters of reference indicate the same or like parts: Fig. 1 is a side elevation, partly in section, showing a device constructed in accordance with the invention; Fig. 2 is a longitudinal section of the knurler of Fig. 1 shown on an enlarged scale; Fig. 3 is a similar view of a modified form of knurler; and Figs. 4 and 5 are views of the conoidal coil showing its adaptation to the shape of the cigar.

In carrying the invention into effect, there is provided a cigar knurling device comprising a conoidal coil of flexible wire for rotatably engaging and yieldingly following irregularities of the head and shoulder of a cigar to smooth its wrapper thereon, and some means is provided for producing a relative rotating movement of the coil and the cigar to be knurled and a support therefor. In the best constructions contemplated, a cigar to be knurled is supported in engagement with the coil and the coil is rotated, and where certain shapes of cigars are to be knurled, there is provided a loose center piece to engage the head of the cigar while

the conoidal coil is in action. In knurling cigars other than those having a ball or round ended head, a loose center piece is not required because cigars of such other forms are not liable to rearrangement of the wrapper at the extreme head end.

The wrappers of half the cigars made are wound on the bunch in a right handed spiral while the other half are wound spirally in the opposite direction. This is due to the fact that the material for the wrappers comes from the right and left sides of the main stem of the tobacco leaf, and are themselves right and left handed, and when wrappers are cut from the leaves they must be wound about the cigar bunches in such a manner as to cause the small branch ribs to lie along the bunches. For this reason these new flexible knurlers must also be made right and left handed because they must revolve in the direction in which the wrapper is wound on the cigar, and the spiral of the coil travels when turned from the head toward the mid-section of the cigar. When turning on a cigar, such a conoidal coil has a tendency to open up circumferentially, thereby producing a more or less delicate touch according to the degree of resiliency of the wire chosen for the coil. The coil is made slightly smaller than it should be to exactly fit a perfect cigar of a predetermined shape. This is done in order to insure that no cigars of the shape for which the knurler is intended will be too small to be successfully knurled. The irregularities, therefore, will be all one way and the flexibility of the coil permits it to expand accordingly.

Referring to Figs. 1 and 2: The knurler shaft 6 is journaled in the horns 7 of a bracket 8 which is attached to the frame of a cigar machine not shown. The shaft 6 is rotated by the bevel gear 9 driven by a bevel gear 10 on a vertical shaft 11, the latter being journaled in the bracket 8 and driven from one of the power shafts of the cigar machine, in connection with which the device is used. One of the horns 7 of the bracket 8 is provided with a stationary bush or sleeve 12 which projects beyond the horn and carries a frame 13 for supporting a cigar C to

be knurled. At its forward end the shaft 6 is provided with an axial slot 14 which is in communication with the central bore 15 of the shaft. Fitting loosely in this bore is a center piece 17 adapted to engage the head of the cigar to prevent displacement of the wrapper thereon at its extreme end, and having a shank 16 in the bore 15 before referred to. The shank 16 is held in place by means of a spring 18 lying in the slot 14 and secured in position by burring or riveting at points 19. The shank 16 is provided with an annular channel 20 into which projects the bent end of the spring 18. Thus, engagement of the bent end of the spring 18 with the annular channel 20 prevents longitudinal displacement of the center piece 17, but does not necessarily make it rotate with the shaft 6.

20 The conoidal coil 21, which forms the knurler proper, is made of flexible wire and its apex is permanently secured by braizing or soldering to an annular shoulder 22 on a collar 23, the latter being bored to fit the shaft 6 and provided with a set screw 24 for attachment thereto. The coil 21 is wound right handed or left handed, in accordance with the wrapper winding of the cigars it is to knurl. The end of the last turn of the coil is tapered off and fitted into a small recess 25 formed in the preceding turn, so that when joined by braizing or soldering, the engaging end of the coil presents a smooth and continuous surface to the entering cigar.

35 When a cigar is inserted in this knurler so that its head engages the center piece 17, the latter is held stationary by the friction of the cigar engaging it, and only the coil 21 rotates about the cigar.

40 In Fig. 3 there is shown a modification of the improved knurler. The shaft 6 is the same as in Fig. 2 and has the same spring 18 in its axial slot 14, but the coil 21 in this case is permanently attached to the center piece 17, having a shank 26 provided with an axial slot 27 engaging the spring 18. The spring 18 thus locks the shank 26 to the shaft 6 and both will revolve about the inserted cigar. The collar 23, in this case, serves merely as a stop to hold the shaft 6 in axial position, resisting the pressure of the cigar bearing against the frame 13. The action of the coil in adapting itself to varying shapes of cigars is illustrated in Figs. 4 and 5. In Fig. 4 the cigar C has entered the coil, only the last or outside turn of the latter is in engagement with the circumference of the cigar, the end or tip of which is still some distance from the center piece of the coil. By pushing the cigar into the knurler, as indicated by the arrow in Fig. 5, the coil 21, due to its flexibility, is shortened axially by pressing its turns toward each other until the head of the cigar

touches the center piece 17. In this position the cigar head will then be in contact with the knurler over its entire surface, with the result that the finished cigar presents a much better appearance than when finished with an ill-fitting knurler of the solid type.

50 By providing the free end of coil shank 26 with a suitable knob or handle 28, the device shown in Fig. 4 may be used with any knurler in the manufacture of hand made cigars.

What is claimed is:

1. A cigar knurling device comprising a conoidal coil of flexible wire for rotatably engaging and yieldingly following irregularities of the head and shoulder of a cigar to smooth its wrapper thereon. 80

2. A cigar knurling device comprising a conoidal coil of flexible wire for rotatably engaging and yieldingly following irregularities of the head and shoulder of a cigar to smooth its wrapper thereon, means for supporting a cigar in engagement with said coil, and means for producing a relative rotating movement of said coil and said support. 85

3. A cigar knurling device comprising a conoidal coil of flexible wire for rotatably engaging and yieldingly following irregularities of the head and shoulder of a cigar to smooth its wrapper thereon, means for supporting a cigar engaged by said coil, and means for rotating said coil. 95

4. A cigar knurling device comprising a conoidal coil of flexible wire for rotatably engaging and yieldingly following irregularities of the head and shoulder of a cigar to smooth its wrapper thereon, a shaft for rotating said coil, and means for supporting a cigar with its axis coincident with the axis of said shaft. 100

5. A cigar knurling device comprising a conoidal coil of flexible wire for rotatably engaging and yieldingly following irregularities of the head and shoulder of a cigar to smooth its wrapper thereon, and means for rotating said coil including a shaft and a member rotating with said shaft and secured to the apex of said coil. 110

6. A cigar knurling device comprising a conoidal coil of flexible wire for rotatably engaging and yieldingly following irregularities of the head and shoulder of a cigar to smooth its wrapper thereon, and means for rotating said coil including a shaft, a collar rotating with said shaft, and a center piece for engaging the head of a cigar in said coil. 115

7. In testimony whereof, I have signed my name to this specification.

120 THURE WILHELM ALM.
